UNITED STATES PATENT OFFICE.

DORSEY F. ASBURY, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

POWER-OPERATED BREECH MECHANISM.

1,229,859.

Specification of Letters Patent. Patented June 12, 1917.

Application filed October 4, 1915. Serial No. 53,962.

To all whom it may concern:

Be it known that I, DORSEY F. ASBURY, a citizen of the United States, and resident of the city of Washington, in the District of Columbia, have invented certain new and useful Improvements in Power-Operated Breech Mechanisms, of which the following is a specification.

My invention relates to power operated breech mechanisms for guns and is an improvement over the breech mechanism illustrated and described in my United States Patent No. 1,185,965, granted June 6, 1916.

The objects of my invention are to provide a hydraulic control brake that will arrest the opening swing of the mechanism and control the swinging of the breech mechanism toward the gun breech and finally arrest the movement of the operating parts when the mechanism is closing; to provide means that will prevent the hydraulic piston rod packing from being under the hydraulic brake pressure; to provide a hydraulic brake piston that moves with the entire stroke of the operating motor piston and controls all movements of the mechanism due to said motor or gravitation; to combine the hydraulic and motor cylinders into one unit; to so construct the motor and hydraulic brake cylinders that

the fluid from either cannot leak into the other; to provide a trap so that the liquid in the hydraulic brake reservoir will always be at atmospheric pressure and which also will prevent any leakage from the reservoir during recoil and counter-recoil of the gun; to provide a rotating cam on the plug rotating crank shaft and a cam follower on the gun whose coaction is in har-

mony with the coaction of the breech plug rotating cams; to extend the crank shaft cam so that its coaction with the cam follower on the gun holds the crank shaft from rotating during the swing of mechanism not affected by the plug rotating cams' action; to have the cam on the shaft in engagement with the roller on the gun before the plug and screw box threads have disengaged to assure continuous smooth action; to provide a latch operated and held by the swing of the mechanism for the purpose of locking the crank shaft against rotation during the swing of mechanism; to provide means for operating the latch while its

latch face is out of contact with the latch face on the crank shaft cam; to taper one side of the extension of the crank shaft cam so that its coaction with the cam follower will gradually move the latch face on the crank shaft cam out of contact with the latch face of the latch before the latter is operated to or from locked position; to provide means for assembling and holding together the crank and cross head bearing; and to provide means for moving the cross head bearing fore and aft in harmony with the fore and aft movement of the breech plug due to the lead of the plug threads.

In the drawings chosen for the purpose of illustrating my invention, the scope whereof is pointed out in the claims,

Figure 1 is a view in elevation of the breech end of a gun embodying my invention, the breech mechanism being shown closed and locked and the operating motor and hydraulic brake in section;

Fig. 2, a plan view of the gun shown in Fig. 1;

Fig. 3, a partial plan view of the gun with the parts in the position they would occupy when the plug rotating cam is just beginning to act in opening the breech or just finishing its action when closing the breech;

Fig. 4, a section on the line 4-4 of Fig. 1 with the parts in the position they would occupy when the plug rotating cam is just beginning to act in closing the breech or just finishing its action in opening the breech;

Fig. 5, a partial plan view with the breech fully open;

Fig. 6, a section on the line 6-6 of Fig. 1;

Fig. 7, a section on the line 7-7 of Fig. 1.

Fig. 8, an enlarged vertical section of the trap; and

Fig. 9, a section on the line 9-9 of Fig. 8.

Referring to the drawings A indicates the rear portion of the gun, B the plug, and C the carrier, which latter swings on trunnions 10 mounted respectively in upper and lower bearing brackets 11. Cam devices M and N are provided for the purpose of translating the movement of the plug in closing the breech and for initiating the swing of the carrier in opening the breech. Each of

these cam devices comprises a roller 12 mounted on the gun and a cam member 13 mounted on the plug. The detail arrangement and construction of said rollers and 5 cam members are fully set forth in my United States Patent No. 1,186,265 granted June 6, 1916.

Rotatably mounted in the carrier C is a shaft 14 the axis of rotation of which is 10 parallel to the pivotal axis of the carrier. The lower end of this shaft embodies a crank 15 which includes a depending crank pin 16 and a lateral extension 17 the purpose of which latter will presently appear. Pivotally connected to the rear face of the plug B is one end of an operating pitman 18. The other end of this pitman terminates in a cross head bearing 19 in which is mounted a cross head 20 which operatively receives the 20 crank pin 16. In order to hold the crank 15, cross-head bearing 19, and cross-head 25 20 in assembled relation I provide the bearing 19 with an inwardly extending flange 21 which, in the locked position of the plug, 30 overlies the extension 17 and as the shaft 14 is rotated in unlocking the plug said flange passes into overlying relation to the crank 15. It will thus be seen that during the plug locking and unlocking rotations of the shaft 35 14 the flange 21 is disposed over the extension 17 or the crank 15 or over both the extension and the crank which assures the parts being held in proper assembled relation during operation. The provision of 40 the extension 17 and flange 21 also enables the cross-head bearing and cross-head to be easily removed from the crank 15 in that, when the plug is locked, the pivotal connection between the pitman and plug can be removed and the pitman swung away from the 45 plug a slight distance to move the flange 21 from overlying relation to the extension 17 when downward movement of the cross-head bearing and cross-head will completely disengage same from the crank and crank pin. A reversal of this operation likewise affords an easy and simple means for assembling the parts. To provide means for moving the cross-head bearing fore and aft in harmony 50 with the fore and aft movements of the breech plug due to the lead of the plug threads, I provide the flange 21 with an inclined face 22 which, during the unlocking rotation of the plug, co-operates with an inclined face 23 on the carrier to move the cross-head bearing aft. To move the cross 55 head bearing forward during locking rotation of the plug I provide the cross-head bearing with another inclined face 24 which 60 co-operates with the adjacent face of the crank 15. An inspection of Fig. 6 will show that the aft movement of the cross-head bearing due to the coaction of the inclined faces 22 and 23 during plug unlocking movement of the pitman 18 will so position the

inclined face 24 with respect to the adjacent face of the crank that during opposite movement of the pitman the coaction of the face 24 with the adjacent face of the crank will impart a forward movement to the cross-head bearing in harmony with the forward movement of the plug due to the lead of the plug threads.

Fixed on the upper end of the shaft 14 is a control cam in the form of an arm 25 75 which is provided on its under side with a substantially V-shaped groove including sections 26 and 27 the outer ends of which open through the same sides of the arm 25. The groove section 26 forms cam walls 28 and 28' 80 each of which is shaped in harmony with the cam faces of the members 13, while the groove section 27 forms a holding wall 29 which diverges with respect to the opposite wall of the groove section from an intermediate point therein to its outer end. Carried by the upper bearing bracket 11 is a rearwardly projecting arm 30 on the outer end of which is mounted a roller 31 which travels in the groove sections 26 and 27 and 90 co-operates directly with the walls 28 and 29 during opening and closing of the breech mechanism for a purpose that will presently appear.

Mounted on the breech end of the gun A 95 is a bracket 32 on which is pivoted a motor cylinder 33. Disposed within the motor cylinder 33 is the section 34 of a hydraulic brake cylinder, said section having at one end a head 35 which is threaded in the motor cylinder 33 and forms one end of the latter. Threaded to the outer end of the head 35 is a hydraulic brake reservoir 36 which has disposed therein and formed integral therewith the section 37 of the hydraulic brake cylinder, said section 37 aligning with the brake cylinder section 34 and forming in conjunction therewith the complete brake cylinder. Communication between the reservoir 36 and the interior of 100 the brake cylinder is afforded by means of passages 38 and 39 formed in the section 37 of the brake cylinder. Mounted in the passage 39 is a ball check valve 40 which serves to prevent flow of liquid from the brake 105 cylinder to the reservoir through the passage 39 while permitting free flow of liquid from the reservoir to the brake cylinder. The wall of the reservoir 36 is provided with a filling opening 41 in which is detachably threaded a plug 42 having a reduced central portion forming an air pocket or trap 43 while the end portions of the plug are provided with openings 44 and 45 respectively. By this construction I am enabled to always maintain the liquid in the reservoir 36 at atmospheric pressure while the provision of the air pocket or trap 43 effectually guards against any leakage of liquid from the reservoir during recoil or 110

counter-recoil of the gun. Slidable on the brake cylinder section 34 is a tubular piston rod 46 one end of which is pivotally connected to a stud 47 on the arm 25 while the other end terminates in a piston head 48. Air is supplied to and exhausted from opposite ends of the cylinder 33 to effect reciprocation of the rod 46 and piston head 48 by means of pipes 49 and 50. These pipes lead to a point directly above the pivot of the cylinder 33 which permits rigid connection, the oscillations of the cylinder being accommodated by the resiliency of the pipes. Slidable in the brake cylinder is a piston rod 51 which has one end connected with the piston rod 46 for movement with the latter while the other end terminates in a piston head 52. The rod 51 slides in a packing 53 suitably mounted in the end of the brake cylinder section 34 remote from the reservoir 36. Formed in the rod 51 and piston head 52 is a by-pass 54, one end of which opens through the reservoir end of the piston head and the other end through the side of the piston rod 51. Mounted in the end of the by-pass 54 is a ball check valve 55 which prevents flow of liquid through the by-pass during movement of the piston head toward the reservoir or in other words during breech closing movement of the piston head 52. Provided within the brake cylinder section 34 is a circumscribing flange 56 which divides the brake cylinder into chambers 57 and 58.

Rotation of the shaft 14 and arm 25 in one direction is limited by means of a stop 59 on the carrier, while rotation of the shaft and arm in the other direction is limited by a projection 60 carried by the arm and adapted to engage the rear end of the gun when the breech mechanism is fully locked. During the first portion of the closing swing of the breech mechanism the stop 59 holds the arm 25 and shaft 14 against rotation and relieves both the shaft and arm of part of the strain. During the last portion of the opening swing of the breech mechanism the arm and shaft are held against rotation by means of a latch 61 pivoted on the carrier. This latch embodies at one end diverging toes 62 and 63 and at its other end a nib 64 adapted to coöperate with a latch face 65 on the arm 25 when said latch is in locked position. The movement of the latch 61 to locked and released positions is automatically effected during the swing of the carrier and to this end I provide a lug 66 on the upper bearing bracket 11 which coöperates with the toe 62 and I further provide said bearing bracket with a recess 67 having a suitably curved inner wall with which the toe 63 coöperates during opening movement of the mechanism to rock the latch to locked position. During closing swing of the mechanism the lug 66 engages the toe 62 and

rocks the latch to and subsequently holds same in released position until the next opening swing of the mechanism. When the arm 25 is disposed against the stop 59 and the latch 61 operated to locked and released positions there will be a slight clearance between the latch face 65 and nib 64 to permit of such operation of the latch without any hard contact between said latch face and nib. The arm 25 is held in proper position during the operation of the latch 61 by engagement of the roller 31 with the wall 29 as will be more fully set forth in the detail description of the operation of the mechanism.

For the sake of clearness I will first describe the operation of opening and closing the breech mechanism without reference to the hydraulic brake. To open the breech when the mechanism is fully locked as shown in Fig. 1 compressed air is admitted to the cylinder 33 through the pipe 49. This air will act against the piston 48 to force same and the rod 46 toward the opposite end of the cylinder and at the same time air in advance of the piston 48 will be relieved through the pipe 50. This movement of the rod 46 acting through the arm 25 will rotate said arm and the shaft 14 to the position shown in Fig. 3. When the parts reach this position the coaction of the cam devices M and N begins and likewise the coaction of the roller 31 with the wall 28. As this wall 28 is shaped in harmony with the cam faces of the members 13 it will be obvious that the shaft 14 can only move in harmony with those movements of the breech plug resulting from the coaction of said cam devices M and N. As the wall 28' is also shaped in harmony with the cam faces of the members 13 it is also obvious that the movements of the plug and carrier due to the coaction of the cam faces 13 with the rollers 12 will have to be completed before the mechanism can swing out beyond such opening swing as is imparted to it by the coaction of the cam devices M and N. When the cam devices M and N reach the termination of their coaction the parts will assume the position shown in Fig. 4 and the roller 31, upon further opening swing of the carrier by the motor, will pass into the groove section 27 and against the wall 29. This engagement of the roller 31 with the wall 29 holds the arm 25. During this holding of the arm 25 by means of the engagement of the roller 31 with the wall 29 the toe 62 of the latch 61 rides up the lug 66 and finally passes out of engagement with said lug and at this time the toe 63 coöperates with the curved base of the recess 67 to move the latch 61 to locked position, said toe 63 finally moving into engagement with the periphery of the bracket bearing 11 to hold the latch in locked position. It will be noted that during the move-

ment of the latch to locked position as just described the arm 25 is held by engagement of the roller 31 with the wall 29 so that no hard contact results during such operation, 5 between the latch face 65 and the nib 64. After the latch 61 has assumed its locked position the roller 31 moves along the tapered portion of the wall 29 and thereby gradually releases the latch face 65 into contact with the nib 64 and prevents any sudden strain being exerted upon the pivot pin of the latch 61. Continued movement of the rod 46 will then swing the mechanism to full open position as shown in Fig. 5, the latch 15 61 serving to lock the arm 25 and the shaft 14 against rotation during such final opening movement of the mechanism.

To close the breech mechanism compressed air is admitted to the cylinder 33 through 20 the pipe 50 while the air on the opposite side of the piston 48 will be relieved through the pipe 49. The resulting movement of the piston 48 and the piston rod 46 acting through the stop 59 will initiate the closing 25 swing of the mechanism. During this movement of the mechanism the roller 31 will enter the groove section 27 and bear against the wall 29 to hold the arm 25 in proper position during the operation of the 30 latch 61. While the roller 31 is in engagement with the wall 29 and just before said roller begins to coact with the wall 28 the free end of the toe 63 reaches the limits of the recess 67 while the toe 62 engages the lug 35 66 with the result that further swing of the mechanism will cause the lug 66 to rock the latch 61 to release position, such movement of the latch of course occurring while the nib 64 is out of hard contact with the latch 40 face 65. Following the movement of the latch 61 to release position the roller 31 begins to coöperate with the wall 28 and at the same time the cam devices M and N begin to coact to initiate the locking rotation 45 of the plug. During this coaction of the cam devices M and N the movements of the shaft 14 will be rendered corresponding to the movement of the plug B produced by the cam devices M and N as a result of the coaction 50 of the roller 31 with the wall 28. At the same time that the coaction of the cam devices M and N to rotate the plug B ceases the roller 31 will pass out of the groove section 26 when further movement of the piston 55 rod 46 will rotate the arm 25 and the shaft 14 to the position shown in Fig. 2 and complete the locking of the breech mechanism.

I will now describe the action of the hydraulic brake device during the opening and closing of the breech mechanism. When the breech mechanism is locked the parts of the hydraulic brake device will be in the position shown in Fig. 1 and as the piston rod 65 51 is connected to the piston rod 46 it will

be obvious that the former will move in unison with the latter during the entire stroke of the piston rod 46 in either direction. As the liquid level in the reservoir 36 is always above the brake cylinder 34 it will 70 be apparent that said cylinder is always filled with liquid. As the opening of the breech mechanism progresses the piston head 52 and the piston rod 51 move toward the opposite end of the brake cylinder and 75 the liquid in said cylinder will flow through the by-pass 54 to the reservoir end of the piston 52 and thereby permit a substantially free stroke of the piston during the unlocking of the breech mechanism, the coaction 80 of the cam devices M and N, and the first portion of the opening swing of the mechanism, at which time it will be obvious the greatest power is required to actuate the parts of the mechanism. As the mechanism 85 approaches its full open position the advance end of the by-pass 54 moves by the flange 56 and into the chamber 58 so that the liquid which is between the piston 52 and flange 56 can no longer flow directly through 90 said by-pass to the reservoir end of the piston 52. The liquid which is now between the piston 52 and the flange 56 must therefore throttle by the piston 52 and by the flange 56 and the resistance offered to this 95 throttling of the liquid controls the final opening movements of the breech mechanism so that same is brought gently to rest in full open position. The provision of the chamber 58 also serves to prevent the packing 53 from being subjected to brake pressure when the opening swing of the mechanism is being arrested for it will be obvious that the liquid throttled into the chamber 58 can pass freely to the reservoir 100 end of the piston 52 through the by-pass 54 and thus prevent the pressure of the liquid in the chamber 58 from being increased. During the movement of the piston 52 just described a vacuum will be formed in the 105 brake cylinder at the reservoir end thereof and if provision is not made to relieve this vacuum a throttling of air by the packing 53 into the brake cylinder will result. I prevent this suction throttling through the 110 medium of the passage 39 and check valve 40 which allows flow of liquid from the reservoir to the brake cylinder during the stroke of the piston referred to. In other words I automatically increase the area of 115 communication between the brake cylinder and reservoir so that sufficient liquid can flow from the reservoir into the brake cylinder under the conditions named to relieve the vacuum and prevent suction throttling. 120 It will be noted that the diameter of that portion of the chamber 34 through which the piston 52 passes after the by-pass enters into communication with the chamber 58 is reduced so as to afford the necessary re- 125 130

sistance to the throttling of the liquid by the piston 52 to produce the requisite braking effect for arresting the opening swing of the mechanism. It will also be noted in 5 this connection that the diameter of the chamber 57 at the end thereof remote from the flange 56 is also reduced for a purpose that will clearly appear from the detail description of the breech closing operation of 10 the brake device.

In closing the breech mechanism it will be apparent that the check valve 55 will prevent flow of liquid through the by-pass 54 which necessitates the liquid throttling by 15 the piston 52 and produces a control stroke which prevents abnormal velocities of swing of the breech mechanism toward the breech. When the closing of the breech is initiated the velocity of the piston 52 is of course very 20 slow and this allows the liquid to pass the piston during the latter's travel in the reduced diameter portion of the brake cylinder adjacent the flange 56 with very little resistance and as the velocity increases the 25 diameter of the cylinder also increases to effect the proper control. The size of the passage 38 is such as will prevent too high swinging velocities of the mechanism. After 30 the cam devices M and N have completed their coaction and the plug threads are partially engaged with the breech chamber threads the piston 52 enters the reduced diameter portion at the reservoir end of the chamber 57 and the necessary braking effect 35 is thereby had to bring the plug gently to rest in fully locked position.

What I claim is:—

1. In a gun, the combination of a movable carrier, a rotatable breech plug, a motor for 40 moving the carrier and rotating the plug, said motor including a reciprocating element, and a brake device including a reciprocating element rigidly connected to and movable with the reciprocating element of 45 the motor during the entire stroke of the latter in either direction to control all movements of the plug and carrier due to said motor or gravitation.

2. In a gun, the combination of a movable carrier, a rotatable breech plug, a motor for 50 moving the carrier and rotating the plug, said motor including a cylinder and a piston, and a brake device including a piston rigidly connected to and movable with the 55 motor piston during the entire stroke of the latter in either direction to control all movements of the plug and carrier due to said motor or gravitation.

3. In a gun, the combination of a movable carrier, a rotatable breech plug, a motor for 60 moving the carrier and rotating the plug, said motor including a cylinder and piston, and a brake device disposed within the cylinder and including a piston rigidly connected to and movable with the motor piston

during the entire stroke of the latter in either direction to control all movements of the plug and carrier due to said motor or gravitation.

4. In a gun, the combination of a movable 70 breech mechanism, a motor for moving the breech mechanism to open and closed positions, said motor including a cylinder and piston one of which is connected to the gun and the other to the breech mechanism, and 75 a brake device including a piston rigidly connected to and moving with the motor piston during the entire stroke of the latter in either direction.

5. In a gun, the combination of a movable 80 carrier, a rotatable breech plug, a motor for moving the carrier and rotating the plug, said motor including a cylinder and piston, and a hydraulic brake device disposed within the cylinder and including a piston 85 rigidly connected to and movable with the motor piston during the entire stroke of the latter in either direction to control all movements of the plug and carrier due to said motor or gravitation. 90

6. In a gun, the combination of a movable breech mechanism, a motor for moving the breech mechanism to open and closed positions, said motor including a cylinder and a piston one of which is connected to the gun 95 and the other to the breech mechanism, a hydraulic brake cylinder within the motor and upon which the motor piston slides, and a brake piston slidable in the brake cylinder and connected to the motor piston to control 100 all movements of the breech mechanism due to said motor or gravitation.

7. In a gun, the combination of a movable carrier, a rotatable breech plug, a motor for 105 moving the carrier and rotating the plug, said motor including a cylinder and piston, a hydraulic brake cylinder within the motor cylinder, a brake piston slidable in the brake cylinder, a piston rod attached to the brake piston and connected to the motor piston, a 110 packing in one end of the brake cylinder through which the piston rod slides, and means for preventing the brake pressure being exerted against the packing during the stroke of the brake piston in the direction of 115 the packing.

8. In a gun, the combination of a movable carrier, a rotatable breech plug, a motor for 120 moving the carrier and rotating the plug, said motor including a cylinder and a piston, a hydraulic brake cylinder within the motor cylinder, a brake piston and piston rod slidable in the brake cylinder and connected to the motor piston, said piston and piston rod having a by-pass opening at one 125 end through the rear of the brake piston and at its other end through the side of the piston rod, a packing in one end of the brake cylinder through which the piston rod slides, and an annular flange on the inner wall of 130

the brake cylinder adapted to be spanned by the by-pass during movement of the piston toward the packing to permit free flow of liquid throttled into the space between the 5 flange and packing to the opposite side of the piston and thereby relieve the packing of brake pressure.

9. In a gun, the combination of a movable breech mechanism, a motor for moving the 10 breech mechanism to open and closed positions, said motor including a cylinder and piston one of which is connected to the gun and the other to the breech mechanism, a hydraulic brake reservoir mounted on one 15 end of the cylinder, a hydraulic brake cylinder disposed within the motor cylinder and reservoir, and a brake piston slidable in the brake cylinder and connected to the motor piston to control all movements of the breech 20 mechanism due to the motor or gravitation.

10. In a gun, the combination of a movable breech mechanism, a motor for moving the breech mechanism to open and closed positions, said motor including a cylinder 25 and piston one of which is connected to the gun and the other to the breech mechanism, a hydraulic brake reservoir mounted on one end of the cylinder, a trap included in the wall of the reservoir and embodying 30 an air pocket communicating with the interior of the reservoir and with the atmosphere, a hydraulic brake cylinder disposed within the motor cylinder and reservoir, and a brake piston slidable in the brake 35 cylinder and connected to the motor piston to control all movements of the breech mechanism due to the motor or gravitation.

11. In a gun, the combination of a movable breech mechanism, a motor for moving the breech mechanism to open and closed positions, said motor including a cylinder 40 and piston one of which is connected to the gun and the other to the breech mechanism, a hydraulic brake reservoir mounted 45 on one end of the cylinder and having a filling opening therein, a plug threaded in said opening and having a reduced central portion forming an air pocket, the ends of said plug being provided respectively with 50 openings whereby said pocket communicates with both the interior of the reservoir and the atmosphere, a hydraulic brake cylinder disposed within the motor cylinder and reservoir, and a brake piston slidable in the brake 55 cylinder and connected to the motor piston to control all movements of the breech mechanism due to the motor or gravitation.

12. In a gun, the combination of a movable carrier, a rotatable breech plug, coacting cam devices on the plug and gun, a shaft rotatably mounted on the carrier and operatively connected with the plug to rotate the latter, means for rotating the shaft 60 and moving the carrier, a roller mounted

on the gun, and a cam fixed on the shaft and co-operating with the roller to render the movements of the shaft corresponding to the movements of the plug produced by the coaction of the cam devices on the plug 70 and gun.

13. In a gun, the combination of a movable breech mechanism, a motor for moving the breech mechanism to open and closed positions, said motor including a cylinder 75 and piston, a hydraulic brake cylinder, a brake piston slidable in the brake cylinder, a piston rod fixed to the brake piston and connected to the motor piston, said piston and piston rod having a by-pass therein 80 opening at one end through the rear of the brake piston and at its other end through the side of the piston rod, and means for checking the flow of liquid through the by-pass during movement of the piston in a 85 direction to effect closing movement of the breech mechanism.

14. In a gun, the combination of a movable carrier, a rotatable breech plug, a motor for moving the carrier and rotating the 90 plug, said motor including a cylinder and piston, a hydraulic brake reservoir mounted on one end of the cylinder, a hydraulic brake cylinder disposed within the motor cylinder and reservoir and having a pair 95 of openings in its wall connecting the interior thereof with the interior of the reservoir, a brake piston slidable in the brake cylinder and connected to the motor piston, and a check valve in one of said openings 100 adapted to close during carrier closing movement of the brake piston and open during carrier opening movement of the brake piston to permit the passage of liquid through said opening during such carrier 105 opening movement of the brake piston to prevent suction throttling.

15. In a gun, the combination of a movable carrier, a rotatable breech plug, a shaft rotatably mounted on the carrier and operatively connected to the plug to rotate the latter, means for moving the carrier and rotating the shaft, a latch pivoted on the carrier for locking the shaft against rotation during movement of the carrier, and 110 means fixed relatively to the gun and co-operating with the latch during movement of the carrier to move said latch to locked and released positions.

16. In a gun, the combination of a movable carrier, a rotatable plug, a shaft rotatably mounted on the carrier and operatively connected to the plug, to rotate the latter, means for moving the carrier and rotating the shaft, an arm on said shaft, a 120 latch on the carrier engageable with the arm to lock the shaft against rotation, means fixed relatively to the gun and co-operating with the latch during movement of the carrier to shift the latch into and 125 130

out of locking relation to the arm, and means on the gun engageable with the arm on the shaft during closing movement of the carrier to hold said arm and shaft 5 against rotation during movement of the latch out of locking relation to the arm.

17. In a gun, the combination with a movable carrier and a rotatable breech plug, of a shaft rotatably mounted on the carrier 10 and operatively connected with the plug to rotate the latter, means for moving the carrier and rotating the shaft, a stop on the carrier, a latch on the carrier, non-elastic means for operating the latch to and 15 from locked position, and an arm on the shaft engaged by the stop and latch during the movement of the carrier between the unlocking and locking rotative periods of the plug to lock said shaft against rotation in either direction.

18. In a gun, the combination of a movable carrier, a rotatable breech plug, a shaft rotatably mounted on the carrier and provided with a latch face, connections 25 between the shaft and plug whereby the rotation of the former will rotate the latter, means for moving the carrier and rotating the shaft, a latch on the carrier engageable with said latch face during movement of 30 the carrier to lock the shaft against plug locking rotation, said latch face being disposed out of engagement with the latch when the shaft is at the limit of its plug 35 unlocking rotation and the latch in locked position, means for moving the latch to locked and released positions during movement of the carrier, and means for holding the shaft at the limit of its plug unlocking rotation during movement of the latch to 40 and from locked position.

19. In a gun, the combination of a movable carrier, a rotatable breech plug, a shaft rotatably mounted on the carrier and provided with a latch face, connections between 45 the shaft and plug whereby rotation of the former will rotate the latter, means for moving the carrier and rotating the shaft, a latch on the carrier engageable with said latch face during movement of the carrier 50 to lock the shaft against plug locking rotation, said latch face being disposed out of engagement with the latch when the shaft is at the limit of its plug unlocking rotation and the latch in locked position, means for 55 moving the latch to locked and released positions during movement of the carrier, means for holding the shaft at the limit of its plug unlocking rotation during movement of the latch to and from locked position, and means for progressively releasing 60 said holding means after the latch has assumed its locked position to permit said latch face to gradually contact with the latch.

20. In a gun, the combination of a movable carrier, a rotatable breech plug, a shaft rotatably mounted on the carrier and operatively connected to the plug to rotate the latter, means for moving the carrier and rotating the shaft, a latch pivoted on the 65 carrier for locking the shaft against rotation during movement of the carrier and non-elastic means operating automatically to move the latch to and from locked position during movement of the carrier. 75

21. In a gun, the combination of a movable carrier, a rotatable breech plug, a shaft rotatably mounted on the carrier, means for rotating the shaft, a pitman having one end pivoted to the plug and its other end terminating in a cross-head bearing, a cross-head 80 operatively mounted in said cross-head bearing, a crank on the shaft operatively connected to the cross-head, and means for moving the cross-head bearing fore and aft in harmony with the fore and aft movement of the breech plug due to the lead of the plug threads.

22. In a gun, the combination of a movable carrier, a rotatable breech plug, a shaft 90 rotatably mounted on the carrier, means for rotating the shaft, a pitman having one end pivoted to the plug, and its other end terminating in a cross-head bearing, a cross-head 95 mounted in said bearing, and a crank on the shaft operatively connected to the cross-head, said cross-head bearing having inclined surfaces co-operating with the carrier and crank during rotation of the latter to move the cross-head bearing fore and aft 100 in harmony with the fore and aft movement of the breech plug due to the lead of the plug threads.

23. In a gun, the combination of a movable carrier, a rotatable breech plug, a shaft 105 rotatably mounted on the carrier, means for rotating the shaft, a pitman having one end pivoted to the plug and its other end terminating in a cross-head bearing, a cross-head 110 in said bearing, and a crank on the shaft operatively connected to the cross-head and detachably interlocking with the cross-head bearing to hold the crank, cross-head and cross-head bearing in assembled relation.

24. In a gun, the combination of a movable carrier, a rotatable breech plug, a shaft 115 rotatably mounted on the carrier, means for rotating the shaft, a pitman having one end pivoted to the plug and its other end terminating in a cross-head bearing, an inwardly directed flange on the cross-head bearing, a cross-head in said bearing, a crank on the shaft operatively associated with the cross-head, and an extension on 120 said crank engaged beneath the flange when the plug is locked to hold the crank and cross-head bearing in assembled relation, said flange being disengageable from the ex- 125

tension by rotation of the cross-head bearing in one direction to effect disassembling of the crank and cross-head bearing.

25. In a gun, the combination of a movable carrier, a rotatable breech plug, coacting cam devices on the plug and gun, a shaft rotatably mounted on the carrier and operatively connected with the plug to rotate the latter, means for rotating the shaft and moving the carrier, a roller mounted on the gun, and a cam fixed on the shaft and co-operating with the roller to render the movements of the shaft corresponding to the movements of the plug produced by the cam devices on the plug and gun.

26. In a gun, the combination of a movable carrier, a rotatable breech plug, a shaft rotatably mounted on the carrier and operatively connected to the plug, a cam on the

shaft, and an element mounted on the gun 20 and coacting with the said cam to initiate rotation of the plug as the latter enters the breech.

27. In a gun, the combination of a movable carrier, a rotatable breech plug, a shaft 25 rotatably mounted on the carrier and operatively connected to the plug, a cam on the shaft, and a roller on the gun co-acting with the cam as the plug enters the breech to initiate locking rotation of said plug and during unlocking rotation of the plug to initiate opening movement of the carrier.

In testimony whereof I hereunto affix my signature in the presence of two witnesses.

DORSEY F. ASBURY.
